KNOCKOUT FOR DIE CASTING MACHINES

Lucian Ring, Detroit, Mich., assignor to Ternstedt
Manufacturing Company, Detroit, Mich., a cor-
poration of Michigan

Application May 17, 1940, Serial No. 335,827

6 Claims. (Cl. 22—94)

This invention relates to the art of die casting and more particularly to an improved ejector and knock-out mechanism for freeing the finished casting from the die.

In the operating cycle of die casting machines in general use, the dies are closed, then molten metal is injected into the die cavity and freezes, the dies are opened and the finished casting is ejected from the die cavity. Where necessary the operating cycle also includes the projection into and subsequent retraction from the die cavity of one or more cores. In the separation of the dies the casting sticks to the cooler die surface but the bond is broken by the action of the ejector. However, the casting also sticks to the surface of the ejector exposed in the die cavity during the casting operation and needs to be removed manually after being ejected from the die. This manual removal is performed by the workman after the completion of each operating cycle and according to usual practice the workman with a pair of long handled pliers steps up to the parted dies and with proper caution inserts the pliers, takes hold of the hot casting, dislodges it from the ejector and lifts it out and deposits it in a suitable receptacle.

It is an object of the present invention to eliminate the manual operation of removing the finished casting and thereby reduce the hazard, effort and time involved by providing mechanism not only to eject the finished casting but to free it completely so that it drops automatically from the machine at the end of the cycle and enables the next casting operation to proceed without delay.

A further object of the invention is to provide a mechanical knock-out device operatively connected with the cooperating die blocks for actuation upon relative die movement to project a member between the separated dies and behind the ejected castings and impart a final lateral movement to the member to strike or push against the casting and break it loose from the ejector.

Other objects and advantages will become apparent during the course of the following specification having reference to the accompanying drawings wherein Figure 1 is a side elevation of a fragment of a die casting machine having the invention applied thereto; Figure 2 is an enlarged view, partly in section, showing the relation of the parts, with the dies in closed position; Figure 3 illustrates the relation of the parts with the dies in fully opened position and Figure 4 is a sectional view taken on line 4—4 of Figure 2.

5 The invention may be incorporated in various types of well known die casting machines and is especially adapted for use with relatively movable dies having a vertical parting line as shown, for example, in United States Patent No. 2,145,-956 to Stern. As illustrated in the drawings such machine consists essentially of a movable die block 1 and a stationary die block 2, the latter having a sprue opening for receiving molten metal from the nozzle 3 of the injection mechanism associated with a melting pot. The stationary die block 2 is bolted rigidly to an upright or standard 4 projecting upwardly from the frame of the machine and the movable die block 1 is mounted on a reciprocating carriage 5 slidably supported on a series of horizontal guide rods 6 fastened at opposite ends in the upright 4 and a similar frame upright 7. Suitable operating mechanism for the carriage 5, such as a piston motor, is connected to the carriage by means of a plunger 8.

10 The usual ejecting mechanism is associated with the movable die 1 and is shown in the drawings as including a projectible member 9 having its outer face cooperating with the die depression and also having a projecting nose portion 10 which in the closed position of the parts, as illustrated in Figure 2, extends into the sprue opening for spreading the incoming hot metal. 15 It will be understood that the type of ejector pin as regards the surface exposed to the die cavity may be varied in accordance with the type of die cavity and the shape to be cast and that the ejector nose illustrated is that usually employed when the die is formed with multiple cavities. The remote end of the ejector 9 is connected with suitable operating mechanism, such as a piston motor indicated at 11.

20 The actuation of the ejector, the die carriage and the metal injecting mechanism are automatically controlled for action in timed sequence. After the dies have been closed the metal is injected into the cavity and the dies then are moved to open position, the finished casting being carried away in the movable die. 25 As the parting of the dies is in progress the ejector pin 9 moves forward and pushes the casting out of the die cavity with the casting remaining suspended and bonded thereto. According to the present invention automatic actuating means is added to the machine to engage the ejected casting and break it loose from the ejector surface. This enables the finished casting to drop from between the parted dies so that the casting cycle may be again set in motion.

without delay. The finished casting falling from the die drop into a suitable receiver which, as indicated in the drawings, may consist of an inclined chute 12 on which the castings slide laterally from the machine. Optionally an endless conveyor belt may be provided to catch the dislodged castings and carry them from the machine. Where quenching is desired the chute may lead to a suitable tank from which the castings are conveyed to the next operation.

The knock-out member illustrated in the drawings includes a reciprocating rod 13 located wholly beyond the dies during the casting operation. It is mounted in a suitable guide block assembly 14 supported on one of the lateral faces of the movable die block 1. The guide block 14 also carries a bearing shaft 15 for a pair of gears 16 and 17 arranged side by side and keyed or pinned together for unison rotation. The teeth of the gear 16 are in mesh with mating teeth on the knock-out rod 13 while the gear 17 is engaged by a reciprocating rack 18 guided in a slot in the block 14 and secured at its end to a bracket 19 on the stationary frame upright 4. Through this operating connection relative motion of the dies is transmitted to the knock-out rod 13 and as the dies are separated the beveled nose 20 on the inner end of the rod 13 is projected into the space between the dies for engagement with the ejected casting.

In the initial engagement the projected end 20 is located behind the ejected casting, as indicated by the broken lines in Figure 3. The straight line motion of the rod 13 is effected by its bearing engagement in the slot of the guide block 14 together with the spring pressed follower 21, as seen particularly in Figure 2. This guide slot is relieved or enlarged at opposite ends, the enlargement being toward the right at the inner portion, as viewed in Figure 2, and toward the left at the outer portion of the guide slot. These enlargements enable the rod 13 to be canted or swung laterally about its bearing engagement with the driving gear 16. The rocking of the knock-out lever is accommodated by the retraction of the spring pressed follower 21 and is effected by the engagement of camming abutments 22 and 23 mounted, respectively, on the outer end of the bar 13 and on the outer face of the guide block 14. The camming abutment 23 being in the path of the abutment 22 upon inward projection of the rod 13 tilts the rod and causes the inner end 20 to exert a push on the ejected casting and knock it loose from the ejector in the manner illustrated in Figure 3. This occurs as the dies reach the end of their parting travel and with the casting removed the dies can be closed at once for the next casting operation. As the dies move toward closed position the movement is transmitted to the knock-out lever 13 causing it to be retracted beyond the mating faces of the dies.

In order that the operator may remain at the controls at the rear of the machine, a suitable mirror or reflecting surface can be positioned opposite the parting line and at proper angle to enable the operator to see between the dies when the machine opens and the castings are ejected. Thus the operator can observe the condition of the casting and any flash formation as well as the knock-out action without leaving the control station and there is eliminated the walking to and

from the parting line for inspection and handling of the parts as was necessary heretofore.

I claim:

- 5 1. For use with a die casting machine having separable parts containing the molding cavity and ejector mechanism to move a completed casting out of the cavity, means to separate the casting from the ejector mechanism including a rack bar fixed to one of said parts, a pair of interconnected gears rotatably carried by the other of said separable parts with one of the gears engaged by said rack bar for rotation incident to relative movement of said parts, a reciprocatory bar having rack teeth engaging the other of said gears and being arranged for projection behind an ejected casting and guide means for the last mentioned bar arranged to cant the bar near its limit of travel for striking the casting loose from the ejector.
- 10 20 2. A die casting machine having in combination with separable dies and an ejector device to move a casting out of the die cavity, of a knock-out lever for projection behind and striking engagement with the ejected casting, guide means carried by one of the dies for mounting said lever and motion transmitting gearing operatively connecting said lever with the other die for moving said lever co-incidently with relative die movement.
- 15 30 3. A die casting machine having in combination with separable dies and an ejector device to move a casting out of the die cavity, of a knock-out member to be projected behind an ejected casting, guide means for said member carried by one of the dies, operative connections between said member and the other die for imparting movement to the member through relative die movement, and camming abutments on the guide and member respectively, adapted for engagement in the projected position of the member to cant the member into striking engagement with the casting.
- 20 40 45 50 55 60 65 70 4. In a die casting machine, a pair of separable dies, an ejector to push a casting from the die cavity, a toothed rack fixed in relation to one of the dies, a gear element carried with the other die in mesh with said rack, a second gear element drive connected with the first gear element and a slideable rack in mesh with the second gear element and arranged for projection into the space between the dies upon die separation to engage an ejector supported casting and break its bond to the ejector.
5. In a die casting machine, relatively movable dies to open and close a die cavity, an ejector associated therewith, a knock-out device to free an ejector supported casting from the ejector, means carried with one of the dies to guide the knock-out device and means operatively connecting the other die and said knock-out device to impart motion thereto upon relative die movement.
6. In a die casting machine having relatively movable dies and an ejector for pushing a completed casting out of the die cavity, a knock-out device movably mounted on one of the dies for freeing the casting from the ejector, motion transmitting mechanism operatively connected to the other die and arranged to impart relative die movement to the knock-out device for the actuation thereof.

LUCIAN RING.
